UNITED STATES PATENT OFFICE.

ADOLPHUS Y. CLARK, OF SHORT CREEK, ARIZONA, ASSIGNOR TO SAFETY FIRST
METAL TIE COMPANY, OF SALT LAKE CITY, UTAH.

RAILWAY-TIE.

1,355,892.

Specification of Letters Patent. Patented Oct. 19, 1920.

Application filed January 26, 1920. Serial No. 354,126.

To all whom it may concern:

Be it known that I, ADOLPHUS Y. CLARK, of Short Creek, in the county of Mohave and State of Arizona, have invented certain new and useful Improvements in Railway-Ties; and I do hereby declare the following to be a full, clear, and exact description of the same, reference being had to the accompanying drawings, forming part of this specification, and to the figures and letters of reference marked thereon.

This invention relates to railway ties in which the body of the tie is made of metal and the direct supports for the rails are small cushion blocks of wood or like material, thus securing all the advantages of a timber tie with the employment of a small quantity of wood. The advantages are the sound-deadening effect and elastic support of the rails; the ability to secure the rails in place with the ordinary spikes and the insulation of the rails so as to render them capable of use in the ordinary signaling systems employing track circuits.

The object of the present invention is to lock the cushion blocks in the tie body in such a manner as to greatly reduce the quantity of metal material necessary for the construction of the tie body.

In the accompanying drawings:

Figure 1 is a perspective view of a tie embodying the present invention.

Fig. 2 is a similar view of the locking elements shown in Fig. 1, removed from the tie body.

Figs. 3 and 4 are like views showing modified forms of locking elements.

As illustrated in the drawings, the body of the tie is formed of sheet metal bent into substantially trough shape, *i. e.*, having vertical sides A and substantially flat bottom A'. A tie of this form possesses a certain inherent resiliency which will relieve the rolling stock from vibrations incident to a rigid bed. However, to increase this effect the rails are supported on cushion blocks B instead of being supported directly on the metal portions of the tie. The cushion blocks B are fitted in the trough-like body in proper position to receive the rails and are of such length as will afford sufficient strength to support the rails and retain the rail fastening means, such as ordinary spikes.

These blocks are preferably formed of

wood and as shown in Figs. 1 and 2 they are held in the tie against vertical displacement by shoulders c formed by turning down the upper edges of locking members C which are positioned in the trough-like body 60 against the ends of the blocks.

To prevent vertical displacement of the locking members C, said members are provided with lateral extensions c' which fit in the longitudinally disposed receiving ends 65 of bayonet slots c² formed in the sides A of the tie body.

In the modification shown in Figs. 3 and 4, the cushion blocks are held against vertical displacement at one end by locking 70 members such as shown in Figs. 1 and 2, but the locking members D used at the other ends of the blocks are formed by a strip of metal struck up from the bottom A' of the trough shaped body, the strip of metal being sufficiently long to permit its upper end 75 d being bent down over the top of the block.

In Fig. 3 the locking member is shown as cut out of the central portion of the tie body bottom, while in Fig. 4 it is shown as cut 80 out of the bottom of the tie body beneath the cushion block. In both instances the aperture formed in the bottom A' permits any water deposited in the trough-shaped body to drain off.

Longitudinal movement of the blocks and locking members in the tie body and bayonet slots is prevented by plates E fitting within the trough-like body at one end of the blocks. The same form of plate is used in 90 the several modifications and as shown it has lateral extensions e slotted as at e'. These slotted extensions fit in the receiving ends of the bayonet slots c² and over the sides A of the tie body, and when the several parts are 95 assembled, the extensions c' on the locking members are forced well into the receiving ends of the bayonet slots so that the locking members and consequently the cushion blocks are securely held down in the trough-like 100 body. In both forms of the device it will be seen that the locking members alone serve to hold the cushion blocks against movement longitudinally of the tie in one direction as well as to hold them against 105 vertical displacement.

If desired, the transverse plates and the adjacent locking members may be provided with apertures F, F' for fasteners, such as screws or nails, to retain the plates, lock- 110

ing members and blocks in their proper relative positions. Such simple fastening means may be easily removed when the blocks are to be renewed or reversed when worn on one side.

The use of small metal plates such as the locking members and transverse plates for locking the cushion blocks against longitudinal and vertical movement renders it possible to form the tie body from a comparatively small sheet of metal, it only being necessary that the sides of the tie body extend up alongside of the cushion blocks a short distance. This, of course, greatly reduces the cost of manufacture of ties of this type.

What is claimed is:

1. A railway tie embodying a metal trough-like body having relatively low sides, a cushion block seated in the trough-like body and projecting above the sides of said body throughout its length to form a rail seat, locking members positioned intermediate the sides of said body and engaging the top of the cushion block for preventing vertical displacement of said block, and a transverse holding plate positioned against one of the locking members and having lateral extensions interlocking with the sides of the trough-like body to prevent relative longitudinal movement of the cushion block and body.
2. A railway tie embodying a metal trough-like body, a cushion block seated in the trough-like body and projecting above the sides of said body to form a rail seat, locking members positioned against the ends of said block and having their upper ends turned down over the top of said block, and a transverse holding plate positioned against one of the locking members and having lateral extensions interlocking with the sides of the trough-like body to prevent relative longitudinal movement of the cushion block and body.
3. A railway tie embodying a metal trough-like body, a cushion block seated in

the trough-like body and projecting above the sides of said body to form a rail seat, a locking member engaging one end and the top of the block to hold said block against longitudinal movement relatively to the trough-like body in one direction and against vertical displacement, a second locking member engaging the opposite end and top of the block, and means interlocking with the sides of the trough-like body to prevent relative longitudinal movement of the block and body.

4. A railway tie embodying a trough-like body having oppositely disposed bayonet slots in its sides, a cushion block seated in the trough-like body and projecting at the top of the body to form a rail seat, a locking member engaging one end and the top of the block to hold said block against longitudinal movement relatively to the trough body in one direction and against vertical displacement, a second locking member engaging the opposite end and top of the block and having lateral extensions fitting in the receiving ends of said bayonet slots, and a transverse holding plate having lateral extensions fitting in the entry ends of said bayonet slots whereby said holding plate will be interlocked with the sides of the trough body to prevent relative longitudinal movement of the block and body.

5. A railway tie embodying a trough-like body having oppositely disposed bayonet slots in its sides, cushion blocks seated in the trough-like body and projecting at the top of said body to form rail seats, locking members engaging the ends and tops of the blocks and having lateral extensions fitting in the receiving ends of the bayonet slots, and transverse holding plates having lateral extensions fitting in the bayonet slots, whereby said holding plates will be interlocked with the sides of the body to prevent relative longitudinal movement of the cushion block and body.

ADOLPHUS Y. CLARK.
